UNITED STATES PATENT OFFICE.

ROBERT JOY, OF OSWEGO, NEW YORK.

FIRE-BOX FOR BOILERS.

1,320,236.

Specification of Letters Patent.

Patented Oct. 28, 1919.

Application filed July 20, 1917. Serial No. 131,847.

To all whom it may concern:

Be it known that I, ROBERT JOY, a citizen of the United States, and resident of Oswego, county of Oswego, and State of New York, have invented certain new and useful Improvements in and Relating to Fire-Boxes for Boilers, of which the following is a specification.

This invention relates to certain improvements in fire boxes for boilers of the locomotive type; and the objects and nature of the invention will be readily understood by those skilled in the art in the light of the following explanation of the accompanying drawings illustrating what I now believe to be the preferred mechanical expression or embodiment of my invention from among other forms, constructions and arrangements within the spirit and scope thereof.

It is an object of my invention to provide an improved boiler fire box having front and rear water legs and side walls composed of water tubes, wherein the tubes are similar, whereby certain economies and advantages are attained.

A further object of my invention is to provide a boiler fire box having side walls comprising water tubes at their upper ends connected with top drums and at their lower ends connected with a mud ring or sill, wherein the water tubes are formed with reduced ends whereby the tubes of a row of closely arranged tubes can be connected with a drum along a straight line and can also be connected to a boiler-plate mud ring along a straight line.

A further object of the invention is to provide a boiler fire box having end water legs, a mud ring, top drums, and side water tubes, wherein the various parts can be composed of boiler plates and tubes.

A further object of the invention is to provide a boiler fire box having its side walls formed by rows of water tubes, with a pair of horizontal longitudinal top drums into which the upper ends of said rows of tubes are connected, so arranged as to maintain the water in the boiler at approximately the desired level and at the same time provide the desired water and steam capacity in said drums.

A further object of the invention is to provide a boiler fire box having a mud ring, side walls comprising rows of vertical water

tubes connected into said ring and longitudinal top drums into which the upper ends of said tubes are connected, with cross water tubes between said drums for equalizing conditions in the drums and also for the purpose of aiding in closing the space between the drums against upward flow of burning gases and products of combustion.

A further object of the invention is to provide improved means and arrangements for the protection of the water tubes and for inclosing the fire box, in water tube fire boxes for boilers.

A further object of the invention is to simplify the construction of water leg and water tube fire boxes for boilers and render the same more economical in construction and maintenance.

A further object of the invention is to improve the construction, formation and arrangement of water tubes employed in water tube and water leg fire boxes for boilers, with the end in view of cheapening the construction and rendering the same more durable than heretofore.

A further object of the invention is to improve the construction of water boxes employed in water leg and water tube fire boxes for boilers with the end in view of rendering said fire boxes more durable and economical in construction.

With these and other objects in view, my invention consists in certain novel features in construction and in combinations and arrangements as more fully and particularly set forth and specified hereinafter.

Referring to the accompanying drawings:

Figure 1, is a longitudinal vertical section (on the line 1—1, Fig. 2) of a fire box embodying my present invention, a portion of the boiler being shown.

Fig. 2, is a cross section on the line 2—2, Fig. 1.

Fig. 3, is a vertical detail section on the line 3—3, Fig. 2.

Fig. 4, is a detail horizontal section on the line 4—4, Fig. 1.

Fig. 5, is a detail horizontal section on the line 5—5, Fig. 1.

Fig. 6, is a detail (somewhat diagrammatical) perspective of the mud ring.

In the drawings, I show a portion of the waist or cylindrical shell 1, of a boiler of

the locomotive type having fire tubes 2. In the embodiment illustrated, the tubes extend rearwardly beyond the vertical plane in which the rear end of shell 1 terminates, and 5 are secured in or to the flue sheet 3.

- An inner or front throat sheet 4 is spaced 10 forwardly from and approximately parallel with the sheet 3 and is formed with an opening receiving the rear end of the shell 1. This sheet 4 is also formed with a forwardly 15 extending flange 5 approximately at right angles to the vertical plane of the sheet, and this flange fits the exterior of the shell and is continuous around the same and is rigidly 20 riveted or otherwise united thereto.

The two sheets 3, 4, are suitably coupled together and depend from the boiler to form a water leg or back at the inner or front end of the fire box. For instance, the 25 sheet 3 is formed with a forwardly extending approximately right angle flange 3^a, and the sheet 4 with a corresponding rearwardly extending flange 4^a. The outer or surrounding edge portions of the sheets are bent or 30 pressed to form these flanges which are continuous around the sheets except at the bottom edges thereof. The edge extremities of these flanges approximately meet, and the flanges are united in any suitable manner as 35 by exterior strap plate 7 overlying the flanges and bridging the joint between the edges of the flanges and united to the flanges by rows of rivets 7^a, or by welding if so preferred. The flanges thus form the vertical 40 edge walls of the water leg, and the portion of the boiler shell around the rear ends of the tubes and extending rearwardly from shell 1.

If so desired, the lower portions of the 45 sheets 3, 4, forming the water leg, can be stiffened and braced by connecting stay bolts 8.

The sheet 3 forms the inner end wall of the fire box, and the outer or firing end of the fire box is formed by a water head or 50 leg comprising a pair of parallel vertical united flanged sheets. For instance, I show this front head comprising inner sheet 9, having its outer edge (except at the bottom 55 of the sheet), forming rearwardly extending approximately right angle flange 9^a, and outer sheet 10 having its outer edge (except at the bottom of the sheet) forming forwardly extending approximately right angle 60 flange 10^a. The edges of these flanges approximately meet and the flanges are united by exterior strap 11 riveted or otherwise united to the flanges. The sheets are also formed with openings and surrounding 65 overlapping riveted flanges to provide one or more fire door openings a.

If so desired, the two sheets 9, 10, can be rigidly braced and stiffened at suitable 70 points by stay bolts 11^a.

The roof or top of the fire box comprises,

in the embodiment illustrated, a pair of horizontal parallel spaced similar longitudinal steam and water drums 12 at their inner ends opening into the boiler and at their outer ends opening into the outer water 75 head or leg.

The sheet 3 is formed with a pair of spaced openings to receive the cylindrical inner ends of these drums and with rearwardly extending approximately right angle 80 flanges 3^b continuous around said openings and snugly fitting and lapping the exteriors of the drums, respectively, and rigidly united thereto in any suitable manner as by riveting.

The sheet 9 of the outer water leg is also formed with a pair of spaced transverse openings aligned with said drums and said sheet is formed with forwardly extending approximately-right angle flanges 9^b continuous around said openings, respectively, and snugly receiving and lapping the exterior surfaces of the cylindrical ends of the 85 drums and united thereto in any suitable manner as by riveting.

The sheet 10 is also formed with a pair of spaced openings aligned with the drums 12 of approximately the same diameter as the openings in sheet 9, and with rearwardly projecting approximately right angle cylindrical flanges 10^b, surrounding said openings, respectively. These flanges and openings receive dished heads 13 secured to the flanges by riveting or in any other suitable manner, and in effect, forming the closed 100 exterior ends or heads of the drums.

The two drums are arranged in the same horizontal plane and are spaced inwardly uniform distances from the outer vertical lines of the fire box and are spaced apart a 105 suitable distance. The interior water spaces of the two drums are placed in direct communication with each other approximately throughout the length of the drums by a series of cross tubes 14, opening into and 110 secured to the drums. These tubes connect approximately the lower portions of the interiors of the drums and are preferably uniformly spaced apart to serve to equalize conditions within the drums and maintain the 115 desired water circulation within the drums. These tubes also serve to support suitable refractory material blocks 15 closing the space between the drums against upward 120 flow of burning gases and products of combustion.

Each side wall of the fire box is formed by a series of upright closely arranged water tubes 16 at their upper ends opening into the drums 12 adjacent that side of the 125 fire box and at their lower ends opening into a mud ring or box forming the base of the fire box. The tubes of a series are arranged parallel with each other and in a straight line with the row or series extend- 130

- ing from the outer water leg or head to the inner water leg or head and are preferably arranged so close together as to almost contact at their adjacent longitudinal surfaces.
- 5 The opposite end portions of each tube are abruptly contracted to form end necks 16^a, at the exteriors of the drum and mud box, and the outer extremities of these necks open into the drums and mud box through 70 perforations or holes formed therein to receive the tubes and are united to the drums and box preferably by any suitable welding process, although if so desired, I can weld the lower end necks of the tubes to the mud 75 box and expand the upper end necks of the tubes in the drums.
- By thus forming the tubes with contracted end necks of the required length, I can arrange the tubes with their bodies or ma- 80
- 20 jor portions approximately contacting and can secure all of the tubes of a row in a straight line along the drum and mud box while using a minimum number of tubes. The contracted necks require such small 85 holes in the drums and mud box that these holes can be arranged in a straight line without removing so much of the material of the drums along such lines as to seriously weaken the drums. In other words, it would 90 be dangerous to form a row of holes of the size required to receive the full diameters of the tubes where the tubes are arranged as closely together as required to form the fire box wall.
- 35 Both side walls of the fire box are formed by rows of similar tubes 16, the tubes are all approximately similar and interchangeable and hence can be economically produced and assembled. Each tube is straight 95
- 40 throughout the major portion of its length with its upper portion slightly curved or deflected laterally to enter the lower portion of the outer side of the adjacent drum 12, so that the upper portions of the fire box 100
- 45 side walls, formed by these duplicate tubes, provide the outer arched portions of the roof of the fire box between the drums and the general vertical outer side lines of the fire box.
- 50 Various means can be provided for completing and insulating the side walls of the fire box against escape of burning gases, etc., between the duplicate tubes and for reducing loss of heat to a minimum. For 105
- 55 instance, I show a suitably packed or insulated steel or other exterior metal casing 17 at the outer sides of the fire box and extended over the drums and including wings or sheets 17^a arranged over and following 110
- 60 the curved upper ends of the tubes to the outer sides of the drums. Between the insulating material at the inner surfaces of casing sheets 17, 17^a, and the upright water tubes 16, I preferably arrange blocks 18 115
- 65 of any suitable refractory or insulating material usually concaved at their inner faces to fit the tubes and close the spaces between the tubes. These blocks preferably form walls at the outer sides of each row of tubes from the outer water leg to the inner wa- 120
- 70 ter leg and throughout the vertical lengths of the tubes.
- I preferably close the spaces between the contracted lower necks of the tubes 16 and protect said necks, by inner and outer series of metal blocks 19 arranged along each row of tubes between the top surfaces of the mud ring or box and the abrupt shoulders of the tubes formed by the contracted necks. Each block has a vertical concavity 125
- 75 at its inner edge to receive and extend approximately half way around a neck so that the blocks of the inner series approximately meet the blocks of the outer series along 80 each row of tubes and are secured together by cross bolts 20 to entirely inclose the necks of the rows of tubes and fill in the spaces between the necks and from the mud box to the abrupt shoulders of the tubes. These 85 comparatively heavy metal blocks also serve 90 to stiffen the structure and protect the ends of the tubes from the fire tools.
- The base of the fire box is formed by a mud ring or box which in the example illustrated is in the form of a rectangular open 95 frame composed of steel or other suitable metal boiler plates.
- The cross or end members 21 of this box are in the form of open top troughs which form the bottom heads or walls of the outer 100 and inner water legs. These members 21 are composed of boiler plates pressed up to U or trough form. The lower edges of the sheets 10, 9, of the outer water leg depend at the outer surfaces of the sides of the outer 105 member 21 and are riveted or otherwise secured thereto while the edge flanges 10^a, 9^a, of said sheets fit the ends of said member and are secured thereto so that the member forms a tight closure for the lower end of 110 the water leg. The inner member 21 is secured to the sheets 3, 4, after the same manner to form the bottom closure for the inner water leg. The two opposite side or longitudinal members 22 of the mud box are in 115 the vertical planes of the rows of water tubes 16, respectively, and are closed at the top to form closed chambers, manifolds, or boxes open at their ends into the cross or trough members 21 and consequently into 120 the outer lower corners of the interiors of the water legs. The top edge walls of these closed hollow members are formed with the straight rows of vertical perforations or holes 23 that receive the lower end necks 125 16^a of the water tubes 16.
- The outer lower corners of the water leg sheets 9 and 3, are notched or cut away to receive the ends of the mud box members 22 and place the interiors thereof in open 130

communication with the interiors of the water legs and to provide flanges 22^a secured to members 22.

It will thus be noted that the water is free to circulate through the ends and side members of the mud ring to and from the water legs and from the mud ring through the upright tubes and into and through the drums to and from the water legs and boiler shell.

The closed chamber-forming members 22 of the mud ring are preferably composed of boiler plates pressed into trough form with each member formed by an upper trough placed in reversed position on a lower trough, the longitudinal edges of the two troughs being united by welding. The ends of the boiler plate end members 21 can be united to the ends of the closed hollow members 22 in any suitable manner as by welding or by riveting together overlapping edges thereof.

I provide a fire box that is not only exceedingly simple and durable in construction and maintenance, but also one composed of parts that can be economically assembled and also that can be economically produced largely from stock material. The box is composed essentially of boiler plates and tubes and I employ regulation or right angle flanges wherever possible. I also attain material advantages by forming the fire box side walls of rows of duplicate tubes.

It is evident that various changes, variations and modifications might be resorted to without departing from the spirit and scope of my invention and hence I do not wish to limit myself to the exact disclosures hereof.

40 What I claim is:—

1. A boiler fire box having a water circulating mud sill, top water circulating means, upright water circulating tubes at their upper ends communicating with said means, the lower ends of said tubes having contracted necks opening into said sill, and blocks on said sill and fitting and closing the spaces between said necks and protecting the necks against injury from within the fire box.

2. A boiler fire box having a water circulating mud sill, top water circulating means, upright water circulating tubes at their upper ends communicating with said means, the lower ends of said tubes having contracted necks opening into said sill, and inner and outer rows of blocks fitting and protecting said necks and closing the spaces between the same.

60 3. A boiler fire box comprising a water-circulating mud sill, rows of closely-arranged upright water circulating tubes

along the outer sides of the fire box having contracted necks opening into said sill, means arranged along the inner sides of 65 said rows and protecting and closing the spaces between said necks, and securing devices for said means.

4. A boiler fire box comprising a water-circulating mud sill, rows of closely-arranged upright water circulating tubes along the outer sides of the fire box having contracted necks opening into said sill, protecting means arranged along the inner and outer sides of said rows and embracing said 75 necks and closing the spaces between the same, and securing devices for said means.

5. A boiler fire box comprising a mud sill; rows of upright water circulating tubes at the sides of the fire box and opening into 80 said sills; water circulating means along the top of the fire box and receiving the upper ends of said tubes and embodying a top longitudinal drum; and an upright water box at the rear end of the fire box and consisting essentially of a front sheet having an opening aligned with said drum and a forwardly extending flange surrounding and fixed to the rear end of the drum and also having a rearwardly-extending edge flange, 85 a rear sheet having a forwardly extending edge flange fixed to said edge flange of the front sheet, said rear sheet having an opening aligned with said drum and a forwardly-extending right angle flange around said 90 opening; and an outwardly dished head closing said opening and fitting within and fixed to said flange around the same.

6. A boiler of the locomotive type having a fire box and provided with a depending water leg and a rear end throat sheet at the front end of the fire box and forming the rear wall of said leg, said tube sheet having transverse openings at the lower outer corners of the water leg and exterior flanges 105 adjacent to said openings; an upright water box at the rear end of the fire box comprising a front sheet having transverse openings at the lower outer corners of the water box and exterior flanges adjacent to 110 said openings; a mud sill having end cross portions secured to and forming the bottom closures of said leg and water box and tubular longitudinal portions fixed to said cross portions and entering the water box and leg 115 through said transverse openings and fixed to said flanges, said longitudinal portions having ends opening directly into the water box and leg transversely through said sheets thereof; and upright water circulating 120 tubes at their lower ends opening into said tubular portions of said sill.

Signed,

ROBERT JOY.
